CLAIM

(21) Appl. No.: **29/157,728**

The ornamental design for decorative, diamond-cut jewelry surface, as shown and described.

(22) Filed: **Mar. 21, 2002**

DESCRIPTION

(51) LOC (7) Cl. **11-01**

FIG. 1 is a plan view of the decorative, diamond-cut jewelry surface of the present invention, located on a phantom or generic jewelry piece.

(52) U.S. Cl. **D11/90**

FIG. 2 is an enlargement of the decorative, diamond-cut jewelry surface of the present invention.

(58) Field of Search 63/15-15.9, 26-31,

FIG. 3 is a cross-section through the diamond-cut jewelry surface of FIG. 2, through lines 3—3 thereof; and,

63/3-4; D11/1, 26-39, 40-42, 43-47, 75-78,
79-80, 89-93, 3, 6, 11-18; 428/596; 59/80

FIG. 4 is a cross-section through the diamond-cut jewelry surface of FIG. 2, through lines 4—4 thereof.

(56) **References Cited**

The broken line showing of the jewelry piece is for illustrative purposes only and forms no part of the claimed design.
